EARRING

William F. Mittendorf, Needham, Mass., assignor
to D. E. Makepeace Company, Attleboro, Mass.,
a corporation of Massachusetts

Application March 29, 1948, Serial No. 17,650

1 Claim. (Cl. 63—14)

1

The present invention relates to an earring and more particularly to a means for attaching an earring to an ear lobe.

Generally, an earring may be attached to an ear lobe by a screw type clamp or other mechanical clamping means which usually cause rounded and smooth surfaces to contact an ear lobe. The contact surfaces are smooth and rounded primarily because the contact area is small and the application of pressure or tension by a screw type clamp or other mechanical clamping means would cause discomfort to the wearer when a greater tension than desired is brought to bear on a small area of the ear lobe by an irregular surface. However, due to the construction of this earring, it is sometimes necessary to apply a greater tension than desired to the ear lobe in order to retain the earring in the desired position. Clamping devices having smooth rounded surfaces which come in contact with an ear lobe are disadvantageous because an earring comprising such clamping devices is subject to slipping from the desired position due to the lack of sufficient gripping action which is common to smooth rounded surfaces.

Other types of earrings have clamping means which are dependent upon the inherent resiliency of the earring material, i. e. plastic material, for attachment to an ear lobe. In such earrings, the applied tension is fixed, being determined by the earring material and the maximum weight of ornamentation which might be expected to be applied to such earring. Furthermore, where resiliency of a material is depended upon for earring clamping purposes, the clamping material is usually non-metallic and as such may not comprise ornamental precious metal.

However, the present invention provides an earring having a resilient metallic material with adjustable tension adapted to securely clamp the earring to an ear lobe with minimum pressure in the ear lobe.

It is an object of this invention to provide an earring adapted to remain securely attached to the ear lobe with a minimum pressure on the ear lobe. It is another object of this invention to provide an earring comprising a resilient metallic material having an adjustable tension. It is a further object of this invention to provide an earring having a minimum of parts for easier manufacture. Other objects and advantages of this invention will appear in the description thereof hereinafter following:

The invention is illustrated in the drawings forming part hereof, in which:

Figure 1 is a perspective elevational view of an

earring constructed in accordance with this invention.

Figure 2 is an enlarged sectional view taken along line 2—2 of Figure 1, and

5 Figure 3 is a perspective elevational view of an earring showing another embodiment of this invention.

The present invention provides an earring which, unlike earrings as heretofore manufactured in which adherence to the lobe of the ear is accomplished by an uncomfortable pressure on the ear lobe brought about by a large tension on a small area of the ear lobe, alleviates discomfort to the wearer by causing a minimum pressure on a substantially large area of an ear lobe and at the same time provides a secure adherence to the ear lobe.

In Figure 1, I have shown an earring with two contact plates 1 and 2 large enough to adhere to a substantially large portion of an ear lobe. The tension necessary to retain the earring in position is provided for by a resilient material shaped to direct a spring tension on plates 1 and 2, such material being in the form of a ring-shaped

25 strip 3 of a beryllium-copper alloy which may be coated with a precious metal or an alloy thereof or of other metals or alloys to provide a multi-layer composite material. The beryllium-copper alloy may comprise from about $\frac{1}{2}\%$ to about $2\frac{1}{2}\%$ beryllium with a preferred beryllium-copper alloy comprising $1\frac{1}{2}\%$ to 2% beryllium. The contact plates, more particularly the faces of the contact plates adjacent to the ear lobe, are provided with horizontal corrugations or ribs 4 in

35 order to impart thereto a greater grip to prevent any possible slipping of the earring from the ear lobe. All surfaces of the plates 1 and 2 or only the outer surfaces may be coated with metal similar to the coating of the ring-shaped structure 3.

40 Although the plates 1 and 2 may be attached to the ring-shaped structure by welding or by other methods of attachment, they may also be integral therewith and the basic assembly may be blanked out of flatstock composite material of precious

45 metal and beryllium-copper alloy prior to the formation of the ring-shaped structure. An indentation 5 is impressed into the strip 3 while in the flatstock stage to increase the spring tension of the material. The forming of the indentation 5 produces a corresponding ridge 5' on the opposite side of the flat stock material and such indentation may be provided for either the outer or inner surface of the ring-shaped structure subsequently formed therefrom. The indentation 5 and ridge

50 5' are shown in section in Figure 2, where the

composition of the finished composite material is also more clearly illustrated in relation to the coating of beryllium-copper **6** with precious metal **7**. Although the indentation is specifically illustrated as V-shaped, it may also be U-shaped or the like, and the strip material may comprise a plurality of such indentations. The indentation effect in the strip material, once the proper amount of tension has been established, will maintain the desired tension. The fact that beryllium-copper can be hardened to have a great deal of spring tension, and that with indentations impressed into the beryllium-copper strip material the spring tension is further aided so that it may be maintained in spite of very frequent flexings or continued pressure while on the ear lobe, provides the basis for an earring according to this invention.

In Figure 3, I have illustrated another embodiment of this invention by providing a wire ring-shaped structure **8** having an inherent tension adapted to keep the contact plates in adherence to an ear lobe. The ring-shaped wire structure may be formed from electroplated wire, or from wire on which precious metals are laminated, said wire structure having the qualities and composition as more particularly described in accordance with the strip material of Figure 1. The ends of the wire used to form the ring-shaped structure may have contact plates welded or soldered thereto, or they may be flattened out to make the gripping sections or plates integral therewith.

The resilient material, i. e. beryllium-copper in accordance with this invention, has such physical properties that the spring tension of such material provided for a minimum tension necessary to keep the earring in position and support the weight of the earring and any ornament attached thereto. The finished article can be adjusted to meet individual tension requirements by simply pressing the ring-shaped structure to have the corrugated surfaces of both contact plates meet when greater tension is required, and the contact plates may be spread in opposing directions to create a lesser tension if required. The adjusted tensions will maintain the desired resiliency.

The earring of this invention is distinguished from other types of resilient materials, such as plastics, whereby in such other materials the

product is manufactured to provide a maximum fixed tension to keep an earring in position, such tension being adapted to support a maximum weight, i. e. earring and supplementary ornaments, and which does not possess an adjustable tension.

Supplementary ornaments may be supported by the earrings of this invention either by attachment to a contact plate **1** or **2**, or by suspension from a mounting on the ring-shaped structure **3**.

With reference to the ring-shaped structure, it is also within the scope of the invention to provide a U-shaped structure, a hexagon-shaped structure and the like, so long as the fundamental characteristics of the invention can apply thereto.

An earring manufactured in conformity with the above description has the advantage of being manufactured easily and rapidly and meets the requirements of an article of jewelry in addition to the several advantages hereinbefore set forth.

What I claim is:

A unitary earring comprising spaced plates adapted for contact on opposite sides of an ear lobe, corrugated contact surfaces on each plate with the corrugations running in a substantially horizontal direction, an adjustably spring tensioned depending ring portion connecting said plates, at least the ring portion being formed of an alloy of copper with beryllium hardened to a high degree of spring tension and capable of frequent flexings to maintain an initially set pressure on the lobe engaging plates, a relatively soft precious metal coating for said alloy that does not affect the tension and flexing qualities thereof, and said ring shaped portion being flat and having a longitudinally extending indentation on one side and a corresponding rib on the other that lie out of the plane of the flat portion.
